BY Sigmund Herzog ATTORNEY

UNITED STATES PATENT OFFICE.

GEORGE GAJDOS, OF NEW YORK, N. Y.

SURGICAL INSTRUMENT.

1,108,737.

Specification of Letters Patent. Patented Aug. 25, 1914.

Application filed April 22, 1914. Serial No. 833,688.

To all whom it may concern:

Be it known that I, GEORGE GAJDOS, a subject of the King of Hungary, and resident of the city of New York, in the county of 5 Kings and State of New York, have invented certain new and useful Improvements in Surgical Instruments, of which the following is a specification.

The present invention relates to a surgical 10 instrument, and has for one of its objects to produce a holder, whereby various forms of surgical needles, or other instruments, may be grasped and held firmly in any position, for instance, for the insertion of the needle 15 and again grasped in any position for the purpose of drawing it through to make the stitch.

Another object of the present invention is to provide a simple and efficient needleholder that may be easily changed to form 20 forceps, nippers or other grasping tools, or scissors by replacing some of its parts.

Another object of the invention is to so 25 construct the instrument that its parts may be easily taken apart for cleansing and readily replaced for use.

With these and other objects in view, which will more fully appear as the nature of the invention is better understood, the 30 same consists in the combination, arrangement and construction of parts hereinafter fully described, pointed out in the appended claim and illustrated in the accompanying drawings, it being understood that many 35 changes may be made in the size and proportion of the several parts and details of construction within the scope of the appended claim without departing from the spirit or sacrificing any of the advantages of 40 the invention.

One of the many possible embodiments of the invention is illustrated in the accompanying drawings, in which:—

Figure 1 is a longitudinal section taken 45 through a surgical instrument, constructed in accordance with the present invention, its parts being shown in their open positions; Fig. 2 is a front elevation of the same, its parts occupying their normal, closed positions; Fig. 3 is a side elevation thereof; Fig. 50 4 is a front elevation of forceps and Fig. 5 of scissors adapted for use upon the instrument.

In the drawings, the numerals 10 and 11 55 indicate the operating handle members of

the instrument. These members are attached to one another by a pivot 12, and normally swung open or apart by a spring 13, that is coiled around said pivot and is disposed within and abuts against the inner 60 faces of said handle members. The pivot 12 is attached to the handle member 10 and is adapted to be seated in a slot 14, that is formed in the handle member 11, the said slot extending at an angle to the longitudinal 65 axis of the member 11 to prevent a disengagement thereof from the handle member 10 under ordinary circumstances, that is to say when the operating handle members are swung not too far apart. To the upper 70 ends of the operating handle members are attached pivots 15, adapted to be received by slots 16, which are formed in the lower ends of the shanks 17 of a pair of nippers 18. The slots 16 extend at an angle to the 75 longitudinal axes of the shanks 17 of said nippers, to prevent a disengagement of said nippers from the handle members under ordinary circumstances. The two elements of the nippers are connected by a pivot, for instance a T-headed stud 19, that is attached to one of said elements and seated in a pivot 80 hole 20 in the other element, said hole being provided with a slot 20' that is adapted in length to receive the stud 19. By such arrangement, the two elements of the nippers can be pivotally locked to one another when the head of the stud is across said slot, and taken apart when the stud head is in register with the said slot.

To the head member 11 is secured, for instance by means of a screw 21, an arc-shaped rack-bar 22. The inner end of this bar abuts against the inner face of the handle member 11, while its outer end projects a suitable distance beyond the same, the center of the arc of said bar coinciding with the pivot 12. To permit the rack-bar to be easily detached from the handle member 11, the latter is provided with a longitudinal slot 23, merging into a circular enlargement 24, the diameter of which is slightly larger than that of the head of said screw. The spindle of the screw is normally seated in the slot 23 and, when properly screwed up, holds the rack bar firmly in position upon the member 11. When the screw is loosened and the rack-bar shifted until the head of said screw is in alinement with the circular enlargement 24, the rack 90 95 100 105 110

bar, together with the screw, can be easily detached from the handle member 11. The teeth of the rack-bar are engaged by a lug 25 upon a pawl 26, that is made in the form 5 of a bellcrank lever. This pawl has a slot 27, in which is seated a pivot pin 28 upon the handle member 10. The pawl is disposed within the handle member 10, its upper end 29 being, however, bent outward 10 and projects outside of the operating handle members near to the pivot 15 upon the member 10, and is thus disposed within easy reach of the thumb of the hand of the operator. A blade spring 30, that engages the 15 pawl 26 and bears against the inner face of the handle member 10, keeps the lug 25 of the pawl in engagement with the teeth of the rack-bar. The spring is also disposed within the handle member 10.

20 The operation of this device is as follows: In Fig. 1 of the drawings the parts of the instrument are shown in their inoperative positions. The surgical needle, or similar instrument to be held, is inserted in any desired position between the gripping 25 jaws of the nippers 18. The user, holding the operating handle members in one hand, forces the same toward each other until the needle is firmly gripped by the jaws of the 30 nippers, the lug of the pawl 26, in co-operation with the teeth of the rack-bar 22, then holding the said jaws closed against the action of the spring 13. The needle is then 35 inserted into the body until its point protrudes beyond the same, when the operator shifts the upper end 29 of the pawl by means of his thumb in the direction of the arrow indicated in Fig. 2 of the drawings, thereby 40 disengaging the pawl from the teeth of the rack-bar and permitting the spring 13 to throw the operating handle members apart, thus releasing the needle. The point of the needle is then again 45 gripped in the manner above described by the jaws of the nippers and drawn through to make the stitch.

It is to be observed that the elements of the needle-holder are constructed in such a manner that they can be readily and con-

veniently taken apart for cleansing purposes.

It is obvious that, instead of the nippers 18, any other suitable instrument may be attached to the handle members, for instance the forceps shown in Fig. 4 of the drawings, or the scissors shown in Fig. 5. Obviously when the scissors are made use of, the pawl 26 is detached from the instrument to permit the said scissors to be operated in the ordinary manner.

What I claim is:-

In a device of the character described, the combination with a hollow handle member provided with a pivot at each of its ends and at a point intermediate said ends, of a second hollow handle member having a pivot at its upper end and a slot extending at an angle to the longitudinal axis thereof at its lower end, the pivot at the lower end of said first mentioned handle member being adapted to be seated in said slot, a nippers-like instrument having slots in the lower ends of the shanks thereof, said slots being adapted to receive the pivots at the upper ends of said handle members, whereby the jaws of said nippers-like instrument are adapted to be closed by forcing said handle members toward each other, a spring for swinging apart said handle members, a rack-bar detachably fastened to said second named handle member, and a spring pressed pawl having a slot in which is adapted to be seated the pivot located intermediate the ends of said first named handle member, said pawl being normally kept in engagement by its spring with the teeth of said rack-bar, but adapted to be disengaged from said rack-bar, whereby said handle members are forced apart by said first mentioned spring and the jaws of said nippers-like instrument opened.

Signed at New York, in the county of New York, and State of New York, this 18th day of April, A. D. 1914.

GEORGE GAJDOS.
